UNITED STATES PATENT OFFICE

162,917

STOCKING

Charles N. Woodrow, York, Pa., assignor to Holl-day Hosiery Mills, Inc., York, Pa., a corporation of Pennsylvania

Application July 19, 1950, Serial No. 11,261

Term of patent 14 years

(Cl. D47—7)

To all whom it may concern:

Be it known that I, Charles N. Woodrow, a citizen of the United States and a resident of York, county of York, State of Pennsylvania, have invented a new, original, and ornamental Design for a Stocking, of which the following is a specification, reference being had to the accompanying drawings, forming a part thereof, wherein:

Figure 1 is a fragmentary rear view of a stocking, showing my new design; and

Fig. 2 is a side view thereof.

The essential features of my design reside in the portions shown in full lines on the drawing.

I claim:

The ornamental design for a stocking, substantially as shown and described.

CHARLES N. WOODROW.
